UNITED STATES PATENT OFFICE.

OSCAR HARTMANN, OF ESSEN-ON-THE-RUHR, GERMANY, ASSIGNOR TO
FRIED. KRUPP, OF ESSEN-ON-THE-RUHR, GERMANY.

COMBINATION-FUSE.

SPECIFICATION forming part of Letters Patent No. 737,229, dated August 25, 1903,

Application filed June 26, 1900. Serial No. 21,662. (No model.)

To all whom it may concern:

Be it known that I, OSCAR HARTMANN, a citizen of the German Empire, residing at Essen-on-the-Ruhr, Germany, have invented 5 certain new and useful Improvements in Combination-Fuses, of which the following is a specification.

In combination-fuses made of a comparatively soft metal—for instance, of aluminum—the parts of the percussion-fuse are apt to be distorted on the striking of the projectile, whereby the action of the fuse is rendered uncertain. It has been attempted to counteract this disadvantage by arranging the 10 parts of the percussion-fuse within a shell projecting into the lower end of the body of the projectile. By this arrangement the parts of the percussion-fuse are protected; but the space occupied by the case reduces the space 15 within the projectile for the reception of balls or bursting charge.

The object of the present invention is to arrange the parts of the percussion-fuse in a manner to protect them against distortion in 20 striking even when they are placed within the fuse-body proper and outside of the bore of the projectile. This object I have accomplished by inclosing the parts of the percussion-fuse within a case of hard steel.

My invention will be best understood when described in connection with the annexed drawing, which shows a section through the axis of the body of a combination-fuse, which otherwise is constructed in the usual well-known manner.

In the drawing the letter A designates the body of the combination-fuse, into which body is inserted from beneath, with its bottom G up, a cup-shaped case F, made of hard 40 steel. The bottom G carries the needle E for the time-fuse and the needle H for the percussion-fuse. The end of the steel case F is closed by a cap K, provided with a perforation which serves as a fire-channel.

By the above-described arrangement the parts of the percussion-fuse are perfectly protected within the steel case F, so that when the projectile strikes they do not share the distortion of the body A, and missing fire is 45 excluded.

What I claim as now is—

1. A fuse having means made of harder material than the body of the fuse to protect a part of the fuse against distortion.

2. A combination-fuse having means inserted within and of harder material than the body of the fuse to prevent the distortion of the percussion-fuse.

3. The combination with a fuse, of a case of metal, harder than the metal of which the fuse is constructed, to surround the working parts and protect them from the distortion of the fuse.

4. In a combination-fuse, a hard-steel case inserted within the body of the fuse and containing the parts of the percussion-fuse; whereby their distortion on striking is prevented and certainty of action insured, substantially as shown and described.

5. A combination-fuse having its body provided with a central cavity, and a hard-steel case inserted into said cavity and closely fitting the same; said case containing the operative parts of the percussion-fuse and serving to protect the latter from distortion on impact, substantially as described.

6. A combination-fuse having its body provided with a central cavity extending inwardly from its base, a hard-steel case inserted into said cavity and closely fitting the same; said case containing the operative parts of the percussion-fuse and serving to protect the latter, a perforated cap at the outer end of the case, and pins attached to the inner end of the case and adapted to strike the primers of the time-fuse and the percussion-fuse, substantially as described.

7. A combination-fuse having its body provided with a central cavity extending inwardly from its base, a hard-steel case closed at its inner end and fitted into said cavity; said case containing the operative parts of the percussion-fuse and provided with an exterior shoulder abutting against the inner portion of the body of the fuse, a perforated cap closing the outer end of the case, and pins attached to the inner end of the case and adapted to strike the primers of the time-fuse and the percussion-fuse, substantially as described.

8. A combination-fuse having its body provided with a central cavity extending in-

wardly from the base thereof, and a hard-
steel case fitted to said cavity and bearing
against the body of the fuse; said case con-
taining the operative parts of the percussion-
5 fuse and serving to protect the latter, sub-
stantially as described.

In testimony whereof I have hereunto set

my hand in the presence of two subscribing
witnesses.

OSCAR HARTMANN.
